US00D960382S

(12) **United States Design Patent** (10) Patent No.: **US D960,382 S**
(45) Date of Patent: ** *Aug. 9, 2022

(54) **MULTIFUNCTIONAL BLACKHEAD REMOVER**

(71) Applicant: **Xu He**, Anhui (CN)

(72) Inventor: **Xu He**, Anhui (CN)

(*) Notice: This patent is subject to a terminal disclaimer.

(**) Term: **15 Years**

(21) Appl. No.: **29/747,150**

(22) Filed: **Aug. 20, 2020**

(51) LOC (13) Cl. **28-03**

(52) U.S. Cl.

USPC **D24/214**

CLAIM

The ornamental design for a multifunctional blackhead remover, as shown and described.

DESCRIPTION

FIG. 1 is a perspective view of a multifunctional blackhead remover showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
